(57) **CLAIM**

The ornamental design for a garment accessory, as shown and described.

DESCRIPTION

FIG. 1 is an enlarged front, top, left side perspective view of a garment accessory showing a first embodiment of my new design; having a row of pleats on the front side and snaps tying the free ends together.

FIG. 2 is a front elevational view thereof.

FIG. 3 is a back elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is an enlarged front, top, left side perspective view of a garment accessory according to a second embodiment of my new design having a row of pleats on the front side and a pair of bows tying the free ends together.

FIG. 9 is a front elevational view thereof.

FIG. 10 is a back elevational view thereof.

FIG. 11 is a left side elevational view thereof.

FIG. 12 is a right side elevational view thereof.

FIG. 13 is a top plan view thereof; and,

FIG. 14 is a bottom plan view thereof.

Shading lines are used to show solid structures and are not intended to indicate surface decoration.
